APPARATUS FOR HEATING COATING MATERIAL

Morton I. Dorfan, Pittsburgh, Pa., assignor, by
mesne assignments, to Koppers Company, Inc.,
a corporation of Delaware

Application June 2, 1943, Serial No. 489,348

4 Claims. (Cl. 126—343.5)

The invention relates to apparatus for heating a tank of coating material into which articles to be coated are dipped, and is particularly applicable to the coating of sheet-like and other articles with materials which have quick air-hardening characteristics, such as bituminous base material, in the manner disclosed in my co-pending patent application Serial No. 489,347, filed June 2, 1943.

The object of the invention is to provide a heating apparatus of the character explained whereby a tank of coating material may be efficiently, economically and uniformly heated to and maintained at a variable desired temperature from side to side and from the top to the bottom of the tank.

The invention is diagrammatically illustrated in the accompanying drawing, of which Fig. 1 is a plan view of the apparatus, and Fig. 2 a vertical sectional view taken on the line II—II, Fig. 1.

The apparatus provided according to this invention includes an open top tank 1 which is preferably made of steel, and an open top casing 2 comprising walls of refractory material surrounding the tank and spaced from the bottom and side walls thereof to form passages for the flow of heated gases to heat the tank. The space between the vertical walls of the casing and tank is divided into a plurality of vertical passages, and that between the bottoms thereof into a plurality of horizontal passages which communicate with the vertical passages. Preferably the vertical passages are formed by I-beams 3 whose outer flanges are anchored in casing 2 and whose inner flanges bear against the side walls of the tank for laterally supporting and strengthening it. This is of special advantage when, as shown, the tank is of sufficient depth and capacity to receive a large number of long sheets such as corrugated steel siding and roofing. Similarly, the passages between the bottoms of the tank and casing are preferably formed by I-beams 4 which rest upon the bottom of the casing and support the tank. While any desired number of passages may be provided, as shown in Fig. 1 three vertical passages 5, 6 and 7 are thus formed at one side of the tank and three passages 5a, 6a and 7a at the opposite side, the latter three communicating with passages 5, 6 and 7, respectively, through horizontal passages 5b, 6b and 7b formed by I-beams 4 between the bottoms of the tank and casing.

In a generally similar manner vertical passages 8 and 8a are formed at one end and ver-

tical passages 9 and 9a at the other end of the tank, the vertical passages 8 and 8a communicating at their lower ends with each other through an opening formed in the web of the I-beam that separates them, and the vertical passages 9 and 9a at the other end of the tank similarly communicating at their lower ends with each other.

Heated gases are supplied to the upper ends of a portion of the vertical passages and are delivered from the upper ends of the remainder thereof. For this purpose the top of the casing is preferably provided with a supply conduit 15 which is channel shape in plan view and extends over the tops of passages 5, 6, 7, 8 and 9, and the casing top is similarly provided with a like shaped delivery conduit 16 which extends over the tops of passages 5a, 6a, 7a, 8a and 9a. Gases, heated in a manner presently to be explained, flow to supply conduit 15 through a supply pipe 17 connected to such conduit, and gases delivered to delivery conduit 16 flow from said conduit through a delivery pipe 18.

Associated with each of the passages means are provided for variably controlling the amount of heated gases flowing through it. Such means preferably consists of a horizontally movable damper 19 at the top of each passage, the damper being slidably mounted between the top of casing 2 and the bottom of supply or delivery conduit 15 or 16. As shown in Fig. 1, these dampers are usually so positioned that the openings to the passages from supply conduit 15 increase in cross sectional area in the direction of flow of the heated gases in supply pipe 17. In other words, the smallest damper opening is that for passage 8, and the size of the damper openings progressively increase for passages 5, 6, 7 and 9. The damper opening from passage 8a to delivery conduit 16 may, as shown, be the same as that for the damper opening for passage 8, and similarly, the damper openings for passages 5a, 6a, 7a and 9a may be the same as those for passages 5, 6, 7 and 9 respectively.

While various means may be provided for heating or forming the heated gases, such gases are preferably products of combustion formed in a heating furnace 25 by burning fluid fuel in it. The fluid fuel may be gas supplied by a line 26 to one end of furnace 25, air for combustion being supplied by a suitable blower 27 driven by a motor 28. The rear end of the furnace is connected to gas supply pipe 17, and its front end to an outlet or delivery pipe 18, in the latter of which there is a fan 29 driven by a motor 30 for

withdrawing gases through delivery pipe 18 from delivery conduit 16 and circulating them through the system. Between fan 29 and the front end of furnace 25, delivery pipe 18 may be provided with a damper-controlled riser 31 for bleeding some of the gases from delivery pipe 18, it being understood that heated gases are continually supplied to the system by the products of combustion in the furnace.

In the use of the heating apparatus, bituminous base or other coating materials may be heated uniformly throughout a coating tank. The temperature to which the coating material is heated may be variably controlled by the burner in furnace 25 and by suitably positioning dampers 19.

According to the provisions of the patent statutes, I have explained the principle and mode of operation of my invention, and have illustrated and described what I now consider to be its best embodiment. However, I desire to have it understood that, within the scope of the appended claims, the invention may be practiced otherwise than specifically illustrated and described.

I claim:

1. An apparatus for heating coating material, comprising an open top casing having a bottom and side walls formed of refractory material, a coating tank within and spaced from the bottom and side walls of the casing, I-beams between the casing and tank forming lateral supports for the side walls of the tank and dividing the space between the adjacent vertical walls of the casing and tank into a plurality of vertical passages, I-beams between the bottom of the tank and the bottom of the casing supporting the tank and dividing the space between said bottoms into horizontal passages communicating with said vertical passages, gas supply and delivery conduits at the top of said casing communicating one with the upper ends of a portion of said vertical passages and the other with the upper ends of the remainder thereof, and means for supplying said supply conduit with heated gases, and for removing them through said delivery conduit, said gases flowing through said passages from said supply conduit to said delivery conduit.

2. An apparatus for heating coating material, comprising an open top casing having a bottom and side walls, a coating tank within and spaced from the bottom and side walls of the casing, partitions between the casing and tank dividing the space between the adjacent vertical walls thereof into a plurality of vertical passages and dividing the space between the bottoms thereof into horizontal passages communicating with said vertical passages, gas supply and delivery conduits at the top of said casing communicating one with the upper ends of a portion of said

vertical passages and the other with the upper ends of the remainder thereof, means for supplying said supply conduit with heated gases and for removing them through said delivery conduit, said gases flowing through said passages from said supply conduit to said delivery conduit, and a damper at each end of each of said passages for variably controlling the amount of heated gases flowing through said passage.

3. An apparatus for heating coating material, comprising an open top casing having a bottom and vertical side and end walls, a coating tank within and spaced from the bottom and side and end walls of the casing, partitions between the casing and tank dividing the space between the adjacent vertical side and end walls thereof into a plurality of vertical passages and dividing the space between the bottoms thereof into horizontal passages communicating with said vertical passages between the sides of the casing and tank, channel-shaped gas supply and delivery conduits at the top of said casing communicating one with the upper ends of said vertical passages at one side and at end portions of the casing adjacent said side, and the other communicating with the upper ends of the vertical passages at the other side and adjacent end portions of the casing, and means for supplying said supply conduit with heated gases and for removing them through said delivery conduit, said gases flowing through said passages from said supply conduit to said delivery conduit.
4. An apparatus for heating coating material, comprising an open top casing having a bottom and vertical side and end walls, a coating tank within and spaced from the bottom and side and end walls of the casing, partitions between the casing and tank dividing the space between the adjacent vertical side and end walls thereof into a plurality of vertical passages and dividing the space between the bottoms thereof into horizontal passages communicating with said vertical passages between the sides of the casing and tank, channel-shaped gas supply and delivery conduits at the top of said casing communicating one with the upper ends of said vertical passages at one side and at end portions of the casing adjacent said side, and the other communicating with the upper ends of the vertical passages at the other side and adjacent end portions of the casing, means for supplying said supply conduit with heated gases and for removing them through said delivery conduit, said gases flowing through said passages from said supply conduit to said delivery conduit, and a damper at each end of each of said passages for variably controlling the amount of heated gases flowing through said passage.
